(57) **CLAIM**

The ornamental design for a modular idli plate, as shown and described.

DESCRIPTION

FIG. 1 is an exploded perspective view of a modular idli plate with various molds showing the new design;
 FIG. 2 is an isometric perspective view of my design;
 FIG. 3 is a top plan view thereof;
 FIG. 4 is a bottom plan view thereof;
 FIG. 5 is a front elevation view thereof;
 FIG. 6 is a back elevation view thereof;
 FIG. 7 is a left plan view thereof; and,
 FIG. 8 is a right plan view thereof.

The design consists of a new modular idli plate with various modular molds.
